ATTORNEY.

UNITED STATES PATENT OFFICE.

CALLENDER I. CALVERT, OF PHILADELPHIA, PENNSYLVANIA.

REIN-HOLDER.

SPECIFICATION forming part of Letters Patent No. 269,258, dated December 19, 1882.

Application filed April 26, 1882. (No model.)

To all whom it may concern:

Be it known that I, CALLENDER I. CALVERT, a citizen of the United States, residing in the city and county of Philadelphia, State of Pennsylvania, have invented a new and useful Improvement in Rein-Holders, which improvement is fully set forth in the following specification and accompanying drawings, in which—

Figures 1. and 4 are top or plan views of 10 rein-holders embodying my invention. Fig. 2 is a section in line xx , Fig. 1. Fig. 3 is a front end view thereof. Fig. 5 is a section in line yy , Fig. 4.

Similar letters of reference indicate corresponding parts in the several figures.

My invention consists of a rein-holder constructed substantially as hereinafter described, whereby it may be conveniently and quickly applied to and removed from the rein.

It also consists of a rein-holder formed with 20 raised guards for preventing lateral displacement of the rein.

It also consists of means, hereinafter described, for positively connecting the rein with 25 the holder in the direction of the length thereof.

Referring to the drawings, A represents the holder, formed of a metal frame, consisting of the front transverse bar, a , the longitudinal side bar, b , the middle transverse bar, c , the 30 longitudinal side bar, d , and rear transverse bar, e , the side bar b connecting the front and middle bars, a c , and the side bar d connecting the middle and rear bars, thus forming two parallel throats, f f' , which are open at the 35 side of the frame.

Rising from the ends of the front and rear bars are lugs B B, and from the center of the rear bar is a horn or hook, C, said lugs and hook being integral with the frame.

The rein is passed over the front bar, then 40 through the throat f and under the middle bar, and finally through the throat f' and over the rear bar, the bite of the frame on the rein causing the latter to take firm hold of the frame

or holder. The hook C is inserted in one of 45 the openings in the rein, thus preventing any slipping or disengagement of the rein in the longitudinal direction thereof. The lugs B serve to embrace the side edges of the rein at opposite places, and thus guard the rein against 50 lateral displacement, whereby the rein is reliably connected with the holder. The open throats f f' permit the ready application of the rein to the holder over and under the respective bars; but when the line is to be detached from the holder it is disengaged from the hook C and alternately drawn laterally through the two throats, thus quickly and 55 conveniently disconnecting it.

Formed or connected with the frame is an 60 arm, D, which terminates in a hook, D', at the rear end of said arm, said arm and hook being preferably formed of metal integral with the frame, which may be covered with leather or other suitable material, thus providing a strong 65 and durable hand-piece which may be grasped by the hand or engaged by the fingers in a quick, easy, and secure manner, and permits great power to be exerted on the reins, the effect of which on the animal being evident. 70

Having thus described my invention, what I claim as new, and desire to secure by Letters Patent, is—

1. A rein-holder formed of parallel bars connected together so as to leave throats on opposite sides, and provided with a horn or hook on the rear bar thereof to prevent disengagement or slipping of the rein. 75

2. A rein-holder formed of parallel bars connected together at their ends so as to leave 80 throats on opposite sides, and provided with a horn or hook on the rear bar thereof and lugs B at the sides of the rein-holder, substantially as and for the purpose set forth.

CALLENDER I. CALVERT.
